**METHOD AND APPARATUS FOR CONTINUOUSLY
REFINING OR IMPROVING MINERAL OILS BY
MEANS OF A SOLID ADSORBENT**

Dieter Ernst August Jünchen, Neu-Alschwil, Switzerland, assignor to Camag Chemieerzeugnisse und Adsorptionstechnik A.G., Basel, Switzerland

Filed July 29, 1957, Ser. No. 674,826

Claims priority, application Germany Sept. 4, 1956

2 Claims. (Cl. 196—46)

The present invention relates to a method and apparatus for continuously refining or improving mineral oils by means of a solid adsorbent, and more particularly, by moving the oil and a granular adsorbent in a countercurrent relative to each other and by thus bringing them into intimate contact with each other.

The method according to the present invention is especially adapted for refining or improving mineral oils, for example, crude distillates having a boiling point of more than 550° F., similar semirefined products, as well as distillation residues and used insulating or lubricating oils, by means of a solid granular adsorbent, preferably aluminum oxide. The adsorbent then adsorbs the undesired ingredients of the oils so that one or more final products will be attained which differ in their degree of refinement.

The known methods of treating mineral oils by means of solid adsorbents for refining or purifying purposes were carried out either by a fixed bed percolation or according to the countercurrent principle. The fixed bed percolation has a series of well-known serious disadvantages. Since such method does not operate continuously, a large number of adsorption containers are required, some of which are not being used in the operation at any particular time. Furthermore, the quality of the products attained varies very considerably in accordance with the change in condition of the adsorbent from time to time. For this reason, many attempts have been made to move liquid oil and solids adsorbents in a countercurrent relative to each other in order to attain a really continuous operation. In one known apparatus, the solids were treated like a liquid and conducted in a continuous current in a downward direction through the liquid by means of gravity, although means had to be provided to loosen up the solids. Such loosening had the disadvantage that it considerably reduced the effectiveness of the adsorbent since the filtering effect thereof was lost. Furthermore, due to such loosening, the main advantage of the application of the countercurrent principle was also lost, namely, that the fresh uncharged adsorbent will always come into contact with the liquid which is already considerably refined, while the adsorbent which is already extensively charged with impurities will act upon the liquid which still contains all impurities.

Another known method which avoids the above-mentioned disadvantages to a considerable extent is used for refining or improving mineral oils and operates substantially as follows:

The oil to be treated is pumped in an upward direction through a vessel which has a sieve plate near its bottom. The sieve plate supports a layer of adsorbent, particularly a prepared clay, through which the oil is forced under pressure. The finally treated oil is then withdrawn from the upper area of the vessel. The adsorbent is replenished from above, while the used-up adsorbent is withdrawn from the lower part of the piled layer through pipes. The adsorbent which still contains a considerable proportion of oil is then washed out by means of a low-boiling solvent in a washing apparatus which operates substantially in accordance with the same principle as the adsorption apparatus. The washed oil

2

is then passed to a stripper and is thereafter returned to the adsorption stage. The adsorbent is dried, which means that the adhering solvent is driven off by being heated indirectly, and the adsorbent is then regenerated in a special regenerating furnace by being heated to a temperature of 900 to 1400° F., whereupon after being replenished with fresh adsorbent it returns to the adsorption stage.

Although better than the first-mentioned method, this last method still has a series of serious disadvantages. The continuous countercurrent engagement between the oil and the adsorbent is made possible by forcing the granular adsorbent, which, similar to a heavy liquid, is conducted by gravity to move in the opposite direction to the oil, both toward and away from the container through relatively narrow pipes. Since pipes are not very well adapted to convey solid materials, the operation of an apparatus of this type is at least to some extent subject to breakdowns. The feeding of the solid adsorbent as if it were a liquid also subjects the same to considerable mechanical abrasion in that it will be ground to a smaller granular size which, in turn, impairs the ability of the oil to pass therethrough.

By fixing the quantitative relationship between the flow of adsorbent and the flow of oil to a definite value, it is also possible to determine the quality of the one final product. However, the mentioned method does by no means permit the simultaneous production of oils of different quality and therefore also not the most favorable utilization of the adsorbent, as will be further explained below.

It is therefore an object of the present invention to provide a continuously operating method and apparatus for refining mineral oils by bringing about a reciprocal action of granular solids and mineral oils relative to each other in a countercurrent flow, and in a manner so as to overcome the disadvantages of the methods and apparatus previously known.

A further object of the present invention is to provide a continuous method of the mentioned type, particularly for refining mineral oils by means of a solid adsorbent, wherein the solids are brought into a countercurrent contact with the oil in such a manner that the adsorbent will be conveyed from below in an upward direction and the oil from above in a downward direction.

Another object of the present invention consists in applying only such conveying means for moving the solid adsorbent which insure such flow to be always free of any difficulty or complications.

A further object of the present invention is to provide a refining method which permits more than one kind of oil to be produced in one apparatus to that the adsorbent will be more fully utilized than in previous methods.

Another object of the present invention is to provide a new apparatus for carrying out the mentioned method.

Further objects, features, and advantages of the present invention will be apparent from the following detailed description of one preferred embodiment thereof, particularly when read with the reference to the accompanying drawings, in which—

FIG. 1 shows a diagrammatic illustration of the course of the different proceedings of the method according to the invention;

FIG. 2 shows a diagrammatic view of an apparatus for carrying out the method according to the invention within the adsorption zone;

FIG. 3 shows a side view of the apparatus according to FIG. 2, turned thereto about an angle of 90°;

FIG. 4 shows a side view of a container used according to the invention for transporting the solid granular material;

FIG. 5 shows a vertical cross section through the container illustrated in FIG. 4;

FIG. 6 shows a plan view of a modification of the container; while

FIG. 7 shows a cross section taken along line 7—7 of FIG. 6.

Referring to the drawings, the adsorption zone of the apparatus according to the invention contains several superimposed containers 1, each of which contains a layer of granular adsorbent of equal height supported on a sieve plate. The liquid to be treated, for example, oil, which is fed from above into the respective uppermost container 1 flows by gravity downwardly and successively through all the superimposed filter containers 1 disposed within the adsorption zone. The oil in its finally prepared form emerges from the lowest container 1 and is then passed through a distributor 24 to storage tanks A and B, as will be subsequently described in greater detail.

The respective uppermost container 1, the adsorbent in which is used to a greater extent than that in the lower containers is from time to time removed from the adsorption zone. All the other containers are then moved upwardly at the same time by means of an elevating mechanism indicated diagrammatically in FIG. 1, so that each individual container 1 then assumes the place which was previously taken up by the container above it, while a new container 1 with fresh adsorbent is inserted at the lower end of the adsorption zone. At this time, the flow of oil emerging from the new lowest container 1 is temporarily interrupted since it first has to be charged with oil before it can again flow out of this container. The oil which then at first emerges from the lowest container has a very high degree of refinement and one considerably above that of the main body of oil which emerges subsequently. A relatively small quantity of this highly refined oil is then passed to the storage tank A by means of the distributor 24, the operation of which may be time-controlled just as the supply of adsorbent. When the degree of refinement decreases because the adsorbent in the lowest container 1 becomes more and more charged with impurities, the main quantity of filtered oil will be conducted to storage tank B.

A special advantage of the method according to the present invention is the fact that the treated oil may thus be subdivided. The quality of the main body of oil which is determined by the rate of flow of oil relative to the adsorbent does not become noticeably worse after the highly refined oil has been withdrawn from the main body at the beginning of the operation (also see the following Table III).

In order to permit the oil to percolate at sufficient speed through the plurality layers of adsorbent in the superimposed containers 1, it is necessary to maintain the viscosity of the oil within the adsorption zone below 20 cst. and preferably between 5 and 10 cst. The viscosity of more highly viscous oils may be reduced by an addition of a neutral solvent, for example, petroleum ether. However, the preferred manner of reducing the viscosity consists in increasing the temperature of the oil within the adsorption zone.

After the container 1 with the spent adsorbent has been removed from the upper end of the adsorption zone, it is moved to the washing zone 25 which operates according to the same principle as the adsorption zone. In this washing zone, the oil adhering to the adsorbent is washed out by means of a suitable solvent, preferably gasoline, petroleum ether, or the like, whereupon the solution is conducted to a stripper 26. The solvent then returns from the upper part of the stripper 26 to the washing zone 25, while the oil which has been washed out is returned from the bottom of stripper 26 to the adsorption zone. The washing of the adsorbent is carried out only to such an extent that the undesirable firmly adsorbed impurities will remain on the adsorbent.

The adsorbent is then freed from the adhering solvent by being heated in a drier 27. Insofar as the present invention is concerned, it is of no consequence whether the adsorbent is washed and thereafter also regenerated within the portable container 1 or whether it is removed from the container and moved through drier 27 and the regenerating furnace 28 by some other conveying means. However, it constitutes a definite advantage that it is possible according to the invention to retain the adsorbent within its container 1 during the entire cyclic process.

In the regenerating furnace 28 which may be of any suitable construction, for example, a revolving cylindrical furnace or the like, the impurities of an organic nature which are adsorbed on the adsorbent are burned off so that the adsorbent will thus be regenerated. If the proportion of organic substances amounts to at least 1.5 percent by weight of the adsorbent, it will not be necessary to add a fuel or external heat. The intensity of the washing process in the washing zone 25 should therefore be limited to arrive at such proportion.

The adsorbent will thereafter return from the regenerating furnace 28 to the adsorption zone, possibly after being replenished with fresh adsorbent.

The adsorbent for carrying out the method according to the invention preferably consists of gamma aluminum oxide of a grain size of 0.02 to 0.2 mm., and preferably of 0.06 to 0.15 mm. Such adsorbent has a series of advantages over the natural or synthetic clays as conventionally used. Among these advantages is the fact that the regeneration may be carried out very easily since the aluminum oxide has a greater thermal resistance than clays. It is thus possible to carry out the regeneration at temperatures of 900 to 1600° F. which may be done without any complicated and expensive cooling devices within the regeneration furnace. Even if the adsorbent should temporarily absorb moisture, this will also not cause any irreparable damage.

However, the method according to the invention is not restricted to the use of aluminum oxide but may also be carried out by means of other adsorbents, such as clays or silicates.

The oils which are suitable for being refined according to the new method are viscous mineral oils of any kind such as, for example, crude distillates having a boiling point above 550° F., semirefined oils, and residues, as well as used technical oils such as insulating oils and lubricating oils including used lubricating oils of internal combustion engines.

The following Table I illustrates the efficiency of the new method in the production of two different oils, as well as the operating data within the adsorption zone. Oil A is the semirefined, acid-treated product of an oil from the Middle East, while oil B is a corresponding crude distillate.

Table I

In the apparatus for carrying out the new method within the adsorption zone according to FIG. 2, a certain quantity of the granular solids, for example, of an adsorbent consisting of gamma aluminum oxide, is placed into each of the above-mentioned containers 1. These containers are supported on and guided by parallel guide rails 2 in a position exactly vertically above each other, and are individually retained in place by locking pawls 3 which only permit a movement in the upward direction. The lowest container 1 is inserted into the lowest locking pawls from the side by means of one or more guide rails 4. The uppermost container may be removed from the apparatus toward one side by means of similar guide rails 4. The liquid, for example, the oil to be refined, is supplied from a storage tank, not shown, through a conduit 5 and a control valve 6. The liquid emerges at 7 and is applied upon the layer of solid material in the uppermost container 1. The liquid then percolates by gravity through one container after the other and through the granular layers of solids therein. After the liquid emerges from the lowest container, it is received by a collecting device 8 which may be designed so that the liquid collected therein at different times may be conducted to different storage tanks.

All of the containers 1 of the apparatus are moved at the same time in the upward direction and against the current of the liquid by means of a suitable elevating mechanism. In the embodiment as illustrated in the drawings this mechanism consists of a movable system of parallel vertical rods 9 which may be moved upwardly and downwardly. Rods 9 carry pickup pawls 10 which are pivotally mounted thereon and are spaced from each other at the same distance as locking pawls 3. They are

also of the same shape and construction as pawls 3 and are adapted to take along the containers during the upward movement of the elevating mechanism, while during the downward movement thereof they slide laterally past the containers which are arrested by the locking pawls. The upward and downward movement of the elevating mechanism is limited by an upper stop member 11 and a lower stop member 12, respectively, so that the height of the stroke will always be slightly larger than the vertical distance between the locking pawls, thus always insuring a proper operation of the mechanism. The elevating mechanism may be driven by any suitable means; thus, for example, the mechanism of a relatively small apparatus may be operated by hand, while one of a larger apparatus may be operated by a motor through a suitable reduction gear.

FIGS. 4 and 5 illustrate a container for receiving the granular solids for use in the apparatus as previously described. The containers may be made of a shape and size so as to comply with the respective requirements of the apparatus. In place of a rectangular shape as illustrated, the containers may also be round. The bottom of each container consists of a sieve plate 21 which is adapted to support a layer of the granular material of the required thickness. If the material is very fine-grained, the sieve plate is preferably divided into a supporting element, for example, a perforated metal plate 21, and a filter element 22 which prevents the fine grains from trickling through plate 21. In special cases, for example, in very large containers, it may be advisable to provide a solid bottom plate with filter nozzles therein. Below the bottom plate, the container is slightly inwardly conical so that the liquid flowing out of it will not flow past the respective lower container but be funneled into it. The upper edge of each container has projecting flanges 23 which are designed so as to insure a proper engagement with pawls 3 and/or 19. If the containers have a round cross-sectional shape, the projecting edge portion is preferably made so as to extend along the entire periphery so that the container may be inserted in any vertical position into the apparatus.

FIGS. 6 and 7 illustrate a container of a special design and of a round cross-sectional shape. Sometimes it may happen that channels will form within the layer of solids in one container which will oppose the flow of the liquid with a smaller resistance than all other parts of the layer. Since the liquid always tends to take the path of least resistance, it will follow these channels so that the layer of solids within this container will only exert a minor filtering and adsorbing action upon the liquid and thus be wasted to a considerable degree. This may be avoided according to the invention, as illustrated in FIGS. 6 and 7, by mounting a plurality of partitions 29 on the perforated bottom 21 of each container 1 so as to divide the container into a plurality of smaller sections 30. Partitions 29 may, for example, be of honeycomb shape, and their height is preferably made slightly smaller than the height of the container wall. These partitions divide the layer 31 of solids within the container into a plurality of smaller separate quantities. Partitions 29 should be higher than layer 31 so that columns of liquid 32 of a certain height will form above the layer. Consequently, if a channel should form in one section 30, only the portion of granular material within that section will not exert its proper filtering and adsorbing action, while all the other portions in the other sections will not be affected but exert their full action. If, on the other hand, the layer portion in one of the sections 30 should become clogged, the liquid pressure therein will increase in accordance with the increasing height of the liquid column 32 above that portion so that the interruption will tend to correct itself. The partitions 29 are preferably made of such a height that above a certain critical level the liquid may run over into the adjacent sections.

The operation of the apparatus according to the invention proceeds as follows:

At certain time intervals one container 1 after another, each having a layer of granular material therein, is inserted into the lowest locking pawls 3. At the same time, the uppermost container is removed from the apparatus. The elevating mechanism is then moved downwardly until the pickup pawls 10 engage under the projecting flanges 23 of each container. During the following upward movement of the elevating mechanism, all containers 1 are simultaneously moved upwardly until they engage into the next-higher locking pawls 3 which hold them in arrested position when the elevating mechanism is again moved downwardly. This procedure is repeated at certain time intervals. During the entire length of the operation, interrupted only during the change of containers, the uppermost container is supplied with liquid which by force of gravity passes successively through the layers of granular solids in the individual containers until it emerges from the lowest container and is received by the collecting container 8. The liquid and solid material thus pass through the apparatus in a countercurrent to each other and exert a very intensive action upon each other.

The contents of the respective container which is removed from the apparatus at the upper end of the elevating mechanism may be subjected outside of the apparatus to a further treatment without being removed from the container. The container may then after a suitable time be reinserted into the apparatus at the lower end thereof, either with the same charge of granular solids or with a new charge.

The upward movement of the elevating mechanism with all containers may proceed at any desired speed. Immediately after the change of containers, they may be lifted within a period of a few seconds which is then followed by a longer period of rest. The upward movement may, however, also be carried out within a longer period between two successive container changes. This will be of advantage particularly in larger apparatus since it will permit a considerable saving in operating power.

Even though this invention has been illustrated and described with reference to the preferred embodiments thereof, it should be understood that it is in no way limited to the details of such embodiments, but is capable of numerous modifications within the scope of the appended claims.

The invention having now been fully disclosed, it is claimed that:

1. An apparatus for the refining of a liquid petroleum product including: an elongated generally vertically disposed zone wherein refining of the petroleum is effected by adsorption; a plurality of individual open-top, foraminous-bottom container having solid side walls for confining a granular adsorbent material while it is conducted through the refining zone; a peripheral flange on each of said containers at its upper end; means for introducing said container means, one at a time, into the lowermost portion of the refining zone; means for elevating said containers comprising a supporting frame suspended in said refining zone and including a plurality of downwardly extending rods depending from said frame for substantially the length of the refining zone; pawls pivotally mounted on said rods for engaging said peripheral flange and for simultaneously advancing each of the container means stepwise upwardly through the refining zone; means for intermittently reciprocating said rods vertically; means for limiting the travel of said frame and said rods to slightly more than the height of one container, at each step; means for admitting a liquid to be refined into the uppermost of said open-top, foraminous bottom containers; means for withdrawing said uppermost container from the refining zone; means for withdrawing refined liquid product from the bottom of the refining zone; and vertically extending guide rails secured to an external support adjacent to said refining zone for maintaining the containers in vertical alignment.

2. The apparatus of claim 1 wherein the individual containers comprise open-top foraminous bottom vessels divided by solid, vertical partition walls into a plurality of separate compartments, each adapted to receive solid adsorbent, the height of the partition walls being slightly less than the height of the solid peripheral walls.
